[57] CLAIM

The ornamental design for a memo holder, as shown and described.

DESCRIPTION

FIG. 1 is a top plan view of a memo holder showing my new design;

FIG. 2 is a bottom plan view thereof;

FIG. 3 is a left side elevational view, the right side elevational view being a mirror image thereof;

FIG. 4 is a front elevational view thereof;

FIG. 5 is a rear elevational view thereof; and
FIG. 6 is a top, left front perspective view thereof, drawn to a reduced scale.

FIG 1

FIG 2

FIG 3

FIG 4

FIG 5

FIG. 6
